DESIGN FOR A PAJAMA SUIT OR SIMILAR ARTICLE

Herman A. Russian, New Haven, Conn.

Application July 3, 1948, Serial No. 147,381

Term of patent 7 years

(Cl. D3—17)

To all whom it may concern:

Be it known that I, Herman A. Russian, a citizen of United States, residing at New Haven, in the county of New Haven and State of Connecticut, have invented a new, original, and ornamental Design for Pajama Suit or Similar Article, of which the following is a specification, reference being had to the accompanying drawing, forming part thereof.

In the drawing:

Fig. 1 is a front perspective view of a pajama suit showing my new design with part of the jacket lifted.

Fig. 2 is a rear perspective view of said pajama suit with part of the jacket lifted.

A dominant feature of the design resides in a pajamas suit comprising a blouse portion and pajama trousers portion substantially as shown in the drawing and particularly in the portion of each leg of the trousers portion of the pajama wherein the rear lower edge portion of each leg of the trousers portion is straight, while the front of each leg portion is formed with an inverted

V-shaped lower edge, with lace flouncing extending around the lower edge of each leg portion, and also assuming the same contour as the shape of the lower edge portion of each leg portion of the trousers.

I claim:

The ornamental design for a pajama suit or similar article, as shown and described.

HERMAN A. RUSSIAN.
